(57) **CLAIM**
The ornamental design for a file storage rolling cart, as shown and described.

DESCRIPTION

FIG. 1 is a perspective view of a file storage rolling cart;
FIG. 2 is a front elevation view thereof;
FIG. 3 is a side elevation view thereof;
FIG. 4 is a top plan view thereof; and,
FIG. 5 is a bottom plan view thereof.

The broken line showing of a set of wheels in the figures is included for the purpose of illustrating environment and forms no part of the claimed design.
